UNITED STATES PATENT OFFICE.

ABRAHAM W. COWEN, OF NEW YORK, N. Y.

DESIGN FOR A NECKTIE.

SPECIFICATION forming part of Design No. 35,662, dated February 4, 1902.

Application filed December 17, 1901. Serial No. 86,315. Term of patent 3½ years.

To all whom it may concern:

Be it known that I, ABRAHAM W. COWEN, a citizen of the United States, and a resident of the city of New York, borough of Manhattan, in the county and State of New York, have invented and produced a new and original Design for a Necktie, of which the following is a full, clear, and exact description, reference being had to the accompanying drawing, forming a part thereof, which is a perspective view of an article of neckwear embodying the features of my design.

The leading features of the design consist in the bow-wings A and B and the central section C, which separates the wings and extends from said wings downward uninterrupted from the wings in the form of a streamer D.

The minor features of the design consist in the side contraction of the central section adjacent to the lower edges of the wings and the taper of the upper edge surface of the said central section.

Having thus described my invention, I claim as new and desire to secure by Letters Patent—

The design for a necktie herein shown and described.

In testimony whereof I have signed my name to this specification in the presence of two subscribing witnesses.

ABRAHAM W. COWEN.

Witnesses:

JOSEPH MARX,
MAX BREIDENBACH.
